Kevin Prince(57) **CLAIM**

The ornamental design for a bullet shaped engine nut, as shown and described.

DESCRIPTION

FIG. 1 is a front elevational view of a bullet shaped engine nut showing our new design, the rear elevational view being a mirror image thereof;

FIG. 2 is a left-side elevational view thereof, the right-side being a mirror image thereof;

FIG. 3 is a cross-sectional view thereof, taken along line 3-3 of FIG. 1;

FIG. 4 is a top front perspective view thereof;

FIG. 5 is a top rear perspective view thereof;

FIG. 6 is a bottom front perspective view thereof; and,

FIG. 7 is a bottom rear perspective view thereof.
